BLASTING EXPLOSIVE DEVICE

James Taylor and William Young, Saltcoats, Scotland, assignors to Imperial Chemical Industries Limited, a corporation of Great Britain

Application April 10, 1935, Serial No. 15,643
In Great Britain April 20, 1934

14 Claims.

(Cl. 102—6)

This invention relates to devices for use in blasting, the said devices being of the kind in which a charge of gas-producing materials, together with a suitable initiating device, is enclosed in a rigid container provided with a closure member adapted to release the gases from the container at a predetermined pressure so that a blasting effect is produced in the borehole, the body of the container being sufficiently strong to withstand the explosion and being capable of re-utilization. The gas-producing charge may comprise a slow burning explosive, such as black-powder, or any other suitable gas forming material such as for example, a highly compressed or liquefied gas. The charge may also comprise a chemical mixture capable of undergoing an exothermic reaction with generation of gas when suitably initiated, although not adapted to react under normal conditions with explosive violence.

In blasting devices of the kind described the gas release member usually takes the form of a rupturable steel disc sealing a vent from the container and held in place by a hollow cap screwed to the container. It has also been proposed to employ a suitably adjusted valve or other mechanical form of release device similarly situated within a hollow cap. Discharge caps of this nature are provided with channels or ports through which the gases escape and these channels or ports have hitherto consisted of a single row of radial apertures formed at right angles to the longitudinal axis of the cap and having a total venting area usually approximately equal to the cross sectional area of the container.

According to the present invention a blasting device of the kind described comprises a container of substantially uniform cross section throughout at least the greater part of its length, and an elongated cap provided with a plurality of rows of venting apertures of about the customary size distributed uniformly over the cylindrical surface of the cap, the total cross sectional area of the venting apertures being considerably greater than the internal cross sectional area of the container. It is preferred that the total area of the venting apertures should be at least twice the internal cross sectional area of the container but preferably not exceeding four times this area although beneficial results may be obtained when the ratio is as great as five to one or even higher.

The venting apertures are preferably located so that their centres lie in a plurality of planes spaced substantially uniformly along the longitudinal axis of the cap and perpendicular thereto. It is preferred that there should be at least

three series of apertures lying in separate planes but preferably not more than five.

Discharge caps constructed in accordance with the present invention permit of very efficient venting of the gases generated in the container over a relatively large area of the borehole. The rapid and efficient venting of the gases minimizes any risk of bursting or cracking of the head.

It will be understood that the caps of the present invention are relatively long (for a given diameter) as compared with the caps hitherto employed in the art. It will also be understood that the amount of material removed from the cap to form the venting apertures must not be so great as to weaken the cap mechanically and the invention provides a method whereby the ratio of the venting area to the internal cross sectional area may be increased considerably without the necessity of increasing the diameter of the cap and hence the diameter of the borehole.

According to a further feature of the invention the venting apertures are located at an acute angle to the longitudinal axis of the discharge cap and in a backward direction in the manner described and claimed for a single row of apertures in pending application No. 752,924.

In order to improve still further the efficient venting of the gases the length of the blasting cap occupied by the venting apertures may be formed with a slightly reduced external diameter as compared with the external diameter of the remaining length of the cap and the diameter of the container.

If desired, a small axial hole may be provided in the head of the cap so that the interior may be cleared by means of a punch if part of the ruptured sealing disc should become jammed therein. Alternatively, the discharge cap may be modified to permit of the expulsion of the sealing disc by suitably increasing the size and modifying the shape of one of the forward apertures. It is necessary, however, simultaneously to modify one of the venting apertures at the remote side of the cap so that the total venting area is still uniform about the longitudinal axis.

Various forms of the invention will now be described with reference to the accompanying drawings in which Figure 1 is a longitudinal section showing a cap in position in a container and constructed in accordance with the invention. Figures 2, 3, 4 and 5 show in longitudinal section alternative forms of cap which may be used with the same container indicated in Figure 1.

Referring to Figure 1, the cap 1 is constructed of

metal is attached to the container 2 by means of a screw thread 3, a bursting disc 4 being interposed between the container and the cap. The external diameter of the cap is the same as that of the container. The internal diameter 5 of the container is uniform throughout substantially the whole length thereof, but is restricted at the end to form a throat 6 adjacent to the bursting disc. The cap is provided with an axial passage 7 and this passage communicates with the exterior by means of three groups of ports 9, 10 and 11. Each group consists of four ports equally spaced around the discharge cap and lying in a plane at right angles to the longitudinal axis of the container and cap. The intermediate group of ports 10 is staggered with respect to the other two groups 9 and 11 so that the radial direction of each of the ports in any row is at an angle of 45° with the direction of ports in each adjacent row. A small axial aperture 8 is provided in the head of the cap for the purpose of clearing the ruptured sealing disc if it should become jammed in the interior.

A typical container for use in the present invention may comprise a cylindrical tube of mild steel 20.5 inches long, having internal and external diameters of 1 1/4" and 1 3/4" respectively, and a constriction at the venting end of 3/4" diameter. With such a container good results may be obtained by employing a bursting disc adapted to rupture at about 13 tons per square inch and a cap constructed in the manner illustrated having an internal diameter of 3/4" and provided with ports of 1/2" diameter. In the form illustrated in which there are 12 ports in all the ratio of the venting area to the internal cross sectional area of the container is approximately 2 : 1.

By comparison with this cap constructed in accordance with the present invention a typical cap hitherto employed in the art as suitable for the same container is provided with one row only of 4 venting apertures of 5/8" diameter, the total venting area being equal to the internal cross sectional area of the container.

Referring to Figure 2, the cap illustrated is designed for use with the same container as indicated in Figure 1, and the reference numerals employed have the same significance as in the description of Figure 1, but in this cap there are provided five rows of ports, three rows 9, 11 and 13 being in line with each other, and two intermediate rows 10 and 12 being staggered with respect thereto at a radial inclination of 45°. All the ports are pierced at an angle of about 60° with the longitudinal axis of the cap. The exterior of the cap is recessed as indicated at the upper end 14 and the lower end 15 so that the cap is reduced in diameter over that part of its length which is occupied by the ports. The cap may be constructed of similar dimensions to that described in Figure 1, it being understood that the length is suitably increased to accommodate the two additional rows of ports. The cap may conveniently be 6 1/4" long excluding the screw-threaded end, the ports being distributed over a length of 4 3/4". The ratio of the total venting area to the cross sectional area of the container is 3.6 : 1.

Referring to Figure 3, the cap is provided with only three rows of ports but in place of one of the ports of the most forward row a deep slot 16 is cut longitudinally in order to permit the escape of the ruptured sealing disc, and this aperture is balanced by a second slot 17 cut

peripherally on the other side of the cap. The axial aperture indicated at the head of the cap as in Figures 1 and 2 is omitted. In the cap illustrated in Figure 4 provision for the escape of the ruptured sealing disc is made by slotting longitudinally two opposite ports in the most forward row 11.

The cap illustrated in Figure 5 is substantially identical with the cap illustrated in Figure 2 with the exception that the ports are at right angles 10 to the longitudinal axis. The dimensions of the cap and the ratio of the venting area to the internal cross sectional area of the container are the same as in the cap illustrated in Figure 2.

We claim:

1. A blasting device of the kind described comprising a container of substantially uniform cross section throughout at least the greater part of its length, and an elongated cap provided with a plurality of rows of venting apertures distributed uniformly over the cylindrical surface of the cap, the total cross sectional area of the venting apertures being at least 3 1/3 times as large as the internal cross sectional area of the throat of said container. 15

2. A blasting device of the type wherein a charge of gas-producing material is enclosed in a pressure-resistant container provided with a member adapted to permit the escape of gases at a predetermined and considerable pressure, said blasting device comprising a container of substantially uniform cross section throughout at least the greater part of its length, but provided with a restricted throat, and an elongated cap provided with at least three but not more than 30 five rows of venting apertures distributed uniformly over the cylindrical surface of the cap, the total cross-sectional area of the venting apertures being at least 3 1/3 but not more than 6 2/3 times the internal cross-sectional area of the 40 throat of said container. 25

3. The blasting device of claim 2, in which the venting apertures in each row are staggered with respect to the venting apertures in each adjacent row. 45

4. A blasting device of the type wherein a charge of gas-producing material is enclosed in a pressure-resistant container provided with a member adapted to permit the escape of gases at a predetermined and considerable pressure, said blasting device comprising a container of substantially uniform cross section throughout at least the greater part of its length, but provided with a restricted throat, and an elongated cap provided with at least three but not more than 50 five rows of venting apertures, the centers of which lie in a plurality of planes spaced substantially uniformly along the longitudinal axis of the cap and substantially perpendicular thereto, the total cross-sectional area of the venting apertures being at least 3 1/3 but not more than 6 2/3 times the internal cross-sectional area of the 60 throat of said container. 55

5. The blasting device of claim 4, in which the venting apertures in each row are staggered with respect to the venting apertures in each adjacent row. 65

6. The blasting device of claim 4, in which the axes of the venting apertures form acute angles with the longitudinal axis of the cap, the apices 70 of which angles point toward the top of said cap.

7. The blasting device of claim 4, in which that portion of the discharge cap which is provided with venting apertures has an external diameter slightly smaller than that of the container. 75

8. A blasting device of the type wherein a charge of gas-producing material is enclosed in a pressure-resistant container provided with a member adapted to permit the escape of gases at a predetermined and considerable pressure, said blasting device comprising a container of substantially uniform cross section throughout at least the greater part of its length, but provided with a restricted throat, and an elongated discharge cap provided with at least three but not more than five rows of venting apertures, the centers of which lie in a plurality of planes spaced substantially uniformly along the longitudinal axis of the cap and perpendicular thereto, the venting apertures in each row being staggered with respect to the venting apertures in each adjacent row, the axes of said venting apertures forming forwardly-pointing acute angles with the longitudinal axis of said cap; and the total cross-sectional area of the venting apertures being at least $3\frac{1}{3}$ but not more than $6\frac{2}{3}$ times the internal cross-sectional area of the throat of said container.
9. The blasting device of claim 8, in which one of the forward apertures of the cap is modified to permit the expulsion of the sealing disc after rupture, a corresponding modification being made in an aperture on the other side of the cap.
10. The blasting device of claim 8, in which that portion of the discharge cap having venting apertures exhibits an external diameter slightly smaller than that of the container.
11. A blasting device of the type wherein a charge of gas-producing material is enclosed in a pressure-resistant container provided with a member adapted to permit the escape of gases at a predetermined and considerable pressure, said blasting device comprising a container of substantially uniform cross section throughout at least the greater part of its length and an elongated discharge cap provided with at least three but not more than five rows of venting apertures distributed uniformly over the cylindrical surface of the cap, the total cross-sectional area of the venting apertures being at least twice but not more than four times the internal cross-sectional area of the container, and at least $3\frac{1}{3}$ but not more than $6\frac{2}{3}$ times the internal cross-sectional area of the throat of said container.
12. A blasting device of the type wherein a charge of gas-producing material is enclosed in a pressure-resistant container provided with a member adapted to permit the escape of gases at a predetermined and considerable pressure, said blasting device comprising a container having internal and external diameters of approximately $1\frac{1}{4}$ " and $1\frac{3}{4}$ " respectively, and a constricted throat of approximately $\frac{3}{4}$ " diameter at the venting end, and an elongated cap provided with twelve ports of approximately $\frac{1}{2}$ " diameter.
13. A blasting device of the type wherein a charge of gas-producing material is enclosed in a pressure-resistant container provided with a member adapted to permit the escape of gases at a predetermined and considerable pressure, said blasting device comprising a container having internal and external diameters of approximately $1\frac{1}{4}$ " and $1\frac{3}{4}$ " respectively, and a constricted throat of approximately $\frac{3}{4}$ " diameter at the venting end, and an elongated cap provided with fifteen ports of approximately $\frac{1}{2}$ " diameter.
14. A blasting device of the type wherein a charge of gas-producing material is enclosed in a pressure-resistant container provided with a member adapted to permit the escape of gases at a predetermined and considerable pressure, said blasting device comprising a container of substantially uniform cross section throughout at least the greater part of its length, and an elongated discharge cap provided with at least three but not more than five rows of venting apertures, the centers of which lie in a plurality of planes spaced substantially uniformly along the longitudinal axis of the cap and perpendicular thereto, the venting apertures in each row being staggered with respect to the venting apertures in each adjacent row, the axes of said venting apertures forming forwardly-pointing acute angles with the longitudinal axis of said cap; one of the forward apertures of said cap being modified to permit the expulsion of the sealing disc after rupture, a corresponding modification being made in an aperture on the other side of said cap, and the total cross-sectional area of the venting apertures being at least twice but not more than four times the internal cross-sectional area of the container.
